US00D583677S

(12) **United States Design Patent**
Harrison et al.

(10) **Patent No.:** **US D583,677 S**
(45) **Date of Patent:** **** Dec. 30, 2008**

(54) **COMBINATION BOTTLE AND SPRAYER HEAD**

(75) Inventors: **Bradley G. Harrison**, Shorewood, WI (US); **Cathal L. Fahy**, Racine, WI (US); **Timothy R. Bartlett**, Racine, WI (US); **Evan A. Sparks**, Madison, WI (US)

(73) Assignee: **S.C. Johnson & Son, Inc.**, Racine, WI (US)

(**) Term: **14 Years**

(21) Appl. No.: **29/277,180**

(22) Filed: **Feb. 16, 2007**

(51) **LOC (8) Cl. 09-01**

(52) **U.S. Cl. D9/685; D9/686**

(58) **Field of Classification Search** D9/682-694, D9/516-575, 435, 436, 447, 448; 222/129, 222/135, 153.01, 153.03, 153.04, 153.09, 222/153.11-153.14, 631, 635, 209, 211-213, 222/215, 321.7-321.9, 372, 373, 378, 379, 222/383.1, 384-386, 398, 400.7, 400.8, 401, 222/402.1-402.25; 215/379, 382, 383, 384; 220/662, 665, 669, 670, 671, 675

See application file for complete search history.

CLAIM

The ornamental design for a "combination bottle and sprayer head," as shown and described.

DESCRIPTION

FIG. 1 is a perspective view showing a first embodiment of a combination bottle and sprayer head, with the bottle shaded to indicate that it is opaque;

FIG. 2 is a front view of the combination bottle and sprayer head of FIG. 1;

FIG. 3 is a left side view of the combination bottle and sprayer head of FIG. 1;

FIG. 4 is a rear view of the combination bottle and sprayer head of FIG. 1;

FIG. 5 is a right side view of the combination bottle and sprayer head of FIG. 1;

FIG. 6 is a top view of the combination bottle and sprayer head of FIG. 1;

FIG. 7 is a bottom view of the combination bottle and sprayer head of FIG. 1;

FIG. 8 is a perspective view showing a second embodiment of a combination bottle and sprayer head that is identical to the embodiment of FIG. 1, except the bottle is shaded to indicate that it is translucent/transparent;

FIG. 9 is a perspective view showing a third embodiment of a combination bottle and sprayer head, with the bottle shaded to indicate that it is opaque;

FIG. 10 is a front view of the combination bottle and sprayer head of FIG. 9;

FIG. 11 is a left side view of the combination bottle and sprayer head of FIG. 9;

FIG. 12 is a rear view of the combination bottle and sprayer head of FIG. 9;

FIG. 13 is a right side view of the combination bottle and sprayer head of FIG. 9;

FIG. 14 is a top view of the combination bottle and sprayer head of FIG. 9;

FIG. 15 is a bottom view of the combination bottle and sprayer head of FIG. 9; and,

FIG. 16 is a perspective view showing a fourth embodiment of a combination bottle and sprayer head that is identical to the embodiment of FIG. 9, except the bottle is shaded to indicate that it is translucent/transparent.

The broken lines showing a trigger in FIGS. 1-3, 5, 8-11, 13, and 16; the broken lines showing a central aperture and screw-top fastener in FIGS. 1-5, 8-13, and 16; the broken lines showing a seam between two halves of the sprayer head in FIGS. 1-2, 4, 6, 8-10, 12, 14, and 16; the broken lines showing circular apertures for fastening two halves of the sprayer head together in FIGS. 1-4, 6, 8-12, 14, and 16; the broken lines showing an outlet in a nozzle of the sprayer head in FIGS. 1-2, 8-10, and 16; the generally oval-shaped broken lines showing planar areas in front and/or rear portions of the bottle in FIGS. 1-16; and the generally oval-shaped broken lines showing a central portion of a bottom surface of the bottle in FIGS. 7 and 15; are included for the purpose of illustrating unclaimed portions of the article in addition to defining the bounds of the claim adjacent the areas enclosed by broken lines.
